UNITED STATES PATENT OFFICE.

HARVEY L. FISHER, OF TOLEDO, IOWA.

WEIGHING-SCALE.

SPECIFICATION forming part of Letters Patent No. 335,909, dated February 9, 1886.

Application filed September 23, 1885. Serial No. 177,934. (No model.)

To all whom it may concern:

Be it known that I, HARVEY L. FISHER, a citizen of the United States, residing at Toledo, in the county of Tama and State of Iowa, have invented certain new and useful Improvements in Scales; and I do declare the following to be a full, clear, and exact description of the invention, such as will enable others skilled in the art to which it appertains to make and use the same, reference being had to the accompanying drawings, and to letters or figures of reference marked thereon, which form a part of this specification.

Figure 1 of the drawings is a representation of a perspective view of the scale complete. Fig. 2 is a vertical section through one of the casings. Fig. 3 is a similar view taken through the opposite casing. Fig. 4 is a transverse section through the scale.

This invention has relation to scales; and it consists in the construction and novel combination of parts, as will be hereinafter fully described, and particularly pointed out in the claims.

Referring by letter to the accompanying drawings, M M' designate the main sills; N, the platform, and O the incasement or cover over the main and connecting levers, P P' designating the main levers, and Q designating the long connecting-lever suspended within the cover O.

R designates one of the hooked blocks from which the long connecting-lever Q is suspended within the incasement O, built immediately over the main sill M.

The outer ends of the main levers P P' are provided on their under edges with knife-edge points P², which rest on chilled cast bearings P³, secured to the main sill and end walls of the incasement, so that said chilled cast bearings P³ occupy the lower corners of the incasement O, wherein they are securely bolted through their vertical and horizontal flanges a b. Near their outer ends the main levers P P' are provided with supporting-links T, which engage supporting-hooks U, secured to the outer faces of the platform-sills V, near each end of the latter, a tie-rod, V', forming the lower fastenings for the supporting-hooks U. The platform N is provided with vertical side boards, W W, having inwardly and down-

wardly beveled upper edges which connect with the under edges of the inner walls of the incasements and protect the scale-works from water, snow, and dust. At the middle of the 55 incasement O is rigidly secured a chilled cast slotted bearing-block, X, having seats X' X', for the reception of the fulcrums or knife-edge points X² X² in the under faces of the blocks X³ X⁴, which latter are securely bolted to the 60 under sides of the main levers P P' at their inner or meeting ends. The long connecting-lever Q is provided in its upper edge, about midway between its ends, with a knife-edge point, Q', which bears against the under face 65 of the upper side of the slotted bearing-block X, which latter forms the fulcrum therefor, and the forward end of this long connecting-lever Q is connected by a rod, Q³, to the scale-beam Q⁴.

In the incasement O' at the opposite side of the platform two main levers, similar to the main levers P P', are fulcrumed in the manner described for these latter levers; but instead of a long connecting-lever, Q, a short 75 connecting-lever, S, is employed in connection with these levers P P', and this lever S may be located in the box immediately at the side of the platform, or it may be located at some distance from the platform, if desired or necessary. The long connecting-lever Q and the short connecting-lever S are provided near their fulcrum points with depending arms S' S'', respectively, which latter are connected by a tie-rod, S³, secured in seats in their lower ends. 80 This tie-rod S³ is secured in place by set-screws S⁵, so that the arms S' S'' may be adjusted thereon. With this construction inclined approaches are used to reach and leave the platform, and no pit is therefore needed where 85 these scales are erected.

Having thus fully described my invention, what I claim as new, and desire to secure by Letters Patent of the United States, is—

1. The combination, with the incasements, the chilled cast end bearings, the slotted middle bearings, and the hooks secured to the covers of the incasements, of the main levers with supporting-links near their outer ends and knife-edge points at their inner ends, the 95 hook-blocks, the long connecting-lever, the short connecting-lever, the tie-rods connect-

ing the platform-sills, and the supporting-hooks secured to said platform-sills, substantially as specified.

2. The combination, with the incasements, 5 the chilled end bearings, the slotted middle bearings, and the hook-blocks connected to the covers of the incasements, of the main levers with knife-edge bearings and supporting-links, the short connecting-lever, the long connecting-lever, the scale-beam, the rod connect-

ing the long and short levers, and the platform with supporting-hooks, substantially as specified.

In testimony whereof I affix my signature in presence of two witnesses.

HARVEY L. FISHER.
